(57) **CLAIM**

The ornamental design for an ECG front end module, as shown and described.

DESCRIPTION

FIG. 1 is a front perspective view of an ECG front end module, illustrating my new design;

FIG. 2 is a back perspective view thereof;

FIG. 3 is a top plan view thereof;

FIG. 4 is a left side view thereof; the right side view being a mirror image thereof;

FIG. 5 is a bottom view thereof;

FIG. 6 is a front end view thereof;

FIG. 7 is a back end view thereof; and,

FIG. 8 is the front perspective view, with cables (shown in phantom) added to show the ECG front end module in a use environment.

1 Claim, 4 Drawing Sheets
